UNITED STATES PATENT OFFICE.

MATT OTTO, OF CAREY, OHIO, ASSIGNOR TO THE NATIONAL LIME & STONE CO., OF CAREY, OHIO, A CORPORATION OF OHIO.

SHAKER-SCREEN.

1,358,103.

Specification of Letters Patent. Patented Nov. 9, 1920.

Application filed February 24, 1919. Serial No. 278,574.

To all whom it may concern:

Be it known that I, MATT OTTO, a citizen of the United States, residing at Carey, in the county of Wyandot and State of Ohio, have invented a certain new and useful Improvement in Shaker-Screens, of which the following is a specification.

My invention relates to improvements in shaker screens such as may be used for screening limestone, coal, sand or any other comminuted or fragmentary materials. It has for one object to provide a new and improved form of self-balancing screen which may be used in any kind of a building without undue vibration. Another object is to provide a light, high speed, large capacity screen which will pass material through it with a minimum of power loss and with a maximum of speed. Other objects will appear from time to time in the specification.

My invention is illustrated more or less diagrammatically in the accompanying drawings, wherein—

Figure 1 is a plan view;

Fig. 2 is a side elevation;

Fig. 3 is a section along line 3—3 of Fig. 2;

Fig. 4 is a detailed elevation of a modified form;

Fig. 5 is a section along the line 5—5 of Fig. 4;

Fig. 6 is a side elevation of a further modified form.

Like parts are indicated by like characters in all the figures.

A is a solid durable base frame or bed made up of a series of separate beams or girders and adapted to be put in place in any structure or on any support or foundation in the usual manner. Upon it this base frame carries pillow blocks A¹ A¹ in which is rotatably mounted a shaft A² upon which is a pulley A³ adapted to be driven from any suitable source of power. At either end of the shaft A² are eccentrics A⁴ A⁵, driving straps A⁷ A⁶ and eccentric rods A⁸ A⁹. These eccentrics are spaced 180 degrees one from the other.

Erected upon the base frame A is an upwardly extending shaker frame B, made up of horizontal and vertical beams bolted or otherwise fastened together. B¹ is a coarse screen mounted for reciprocation on the links B² downwardly depending from the

frame B. These links are mounted on the 55 shafts B³ in bearing blocks B⁴ and are outside of the frame B and support by means of bearings as shown the screen shafts B⁵ which extend outwardly beyond the frame and support the coarse screen B¹ by means 60 of saddle clips B⁶. The connecting rods A⁹ are pivoted on one of said shafts B⁵ so that as the eccentric driving shaft rotates and carries the eccentric with it the upper coarse screen will be reciprocated.

It will be noted that the upper coarse screen is located between the cross pieces of the upper frame but that the hangers or links upon which it is swung are located on the outside, thus the whole assembly takes 70 up a minimum of room and all the moving parts are easily gotten at for adjustment, change and repair.

C is a lower screen frame mounted within the supporting housing or framework and supported on the upwardly extending links C¹ C¹ which are pivoted on shafts C² C² extending through the pillow blocks C³ C³ on the frame work A. The eccentric rods A⁸ A⁸ engage one of the shafts C⁴ so that 80 as the eccentric shaft rotates the screen will be reciprocated. It will be noted that since the two eccentrics are separated by an angle of 180 degrees the two screens will reciprocate in opposite directions and there will 85 thus be a very large degree of balance between them. C⁵ is a chute which discharges material from any suitable source onto the screen B¹ adjacent one end. As the screen reciprocates the material passes down toward the left, the fine particles falling through, the coarse particles going on until they are discharged over the end of the screen onto a chute C⁶. The particles which fall through the screen B are caught on the 90 screen C somewhere along its length and pass on with those that are too coarse to pass through until they are discharged into the chute C⁷. The fines which go through are caught in the hopper C⁸. You will notice 95 that this hopper C⁸ extends through the entire length of the screen C so that the material no matter where discharged is caught in the hopper. It will also be noted that the screen B¹ is above the screen C for substantially its entire length so that anything that is discharged through the screen B¹ will 100 be caught by the screen C and thus all ma-

terial will be properly screened, and properly classified into three different classes.

In order to cushion the shock of changing direction and in order to assist in the smooth running balance of the device, I have tied up the two reciprocating screens by spring tie members which tend to exert at all times a yielding pull on the screens normally turning them to their central position and resisting their movement away from the central position in both directions. These springs are so arranged that the farther the screen moves in the opposite direction, because they always move toward or 15 from one another and never in the same direction, the harder will be the pull of the spring and to assist in reducing vibration and balancing the screen.

I have shown these balancing springs in 20 several forms, the first form, consists in two open springs arranged in a pair and while probably cheaper I am inclined to prefer the other form because of its greater durability and accuracy. I have described 25 first, however, the form shown in Figs. 2 and 3.

D D are yokes pivoted on the shaft B⁵ C⁴. These yokes extend across and terminate in arms through which pass loops D¹ D¹ 30 there being one loop on either side of each shaft B⁵ C⁴. Coil tension springs D² are attached to the loops D¹ D¹ being so positioned that when the two screens are in the central position there is still a considerable 35 tension upon these springs. The springs being of the same strength balance each other and hold the yoke substantially parallel. D³ is a pipe or rod extending downwardly from one of the yokes D in slidable 40 engagement with a pipe or rod D⁴ extending upwardly from the other yoke D. A grease cup D⁵ on the rods D³ communicates with the interior thereof and with the exterior of the rod D⁴ whereby grease may be moved 45 under pressure to lubricate both of the yokes D where they ride upon the shaft D⁵ C⁴. There will be a sliding movement of these 50 two tubes or rods one upon the other as the screens move back and forth, and these two rods tend to assist the spring yoke couples in holding the parts together and to prevent looseness and play.

Referring now to the form shown in 55 Figs. 4 and 5, E is a yoke mounted on the shaft B⁵. Downwardly extending from this yoke is a cylindrical lug E¹ in which is screwthreaded the piston rod E² carrying at its end a piston E³ having an enlarged annular head E⁴. E⁵ is a yoke mounted for 60 rotation on the shaft C⁴. It is provided with an upwardly extending screw-threaded collar E⁶ in which is screw-threaded a cylindrical housing E⁷ terminating at its upper end in a screw-threaded aperture cap E⁸. The aperture in this cap is in slidable 65

engagement with the lug E¹. E⁹ is a compression spring contained within the housing E⁷ and adapted to be compressed between the cap E⁸ and the flange E⁴, the flange E⁴ being also in slidable engagement 70 with the housing E⁷. This housing provides a grease container in which the spring reciprocates. The grease, of course, keeps the spring in proper condition as well as the bearing surfaces between the flange E⁴ 75 and the housing E⁷ and between the walls of the aperture of the cap E⁸ and the lug E¹.

In Fig. 6 I have shown a modified form in which the driving shaft is located within the supporting frame. In this form I 80 have shown the further modification of the spring suspension in that the springs D⁶ there shown are simply coil springs pinned to the screens.

It is possible to substitute in either form 85 of my invention, a crank shaft and connecting rods in place of the eccentric.

It will be evident that while I have shown in my drawings an operative device, still many changes might be made in size, shape 90 and arrangement of parts without departing materially from the spirit of my invention and I wish, therefore, that my drawings be regarded as in a sense dia- 95 grammatic.

The use and operation of my invention are as follows:—

When power is applied to the main drive shaft and it rotates, the two eccentrics will 100 rotate with it. Since they are separated by an angle of 180 degrees and since they are connected by links one to each of the reciprocating screens, it will be evident that these screens will work back and forth their movement being separated by an angle of 180 degrees that is, they will be moving in opposite directions at all times, and when the upper one is at the right hand limit of its excursion the lower one will be at the left hand limit of its excursion and vice versa. Since 110 the links upon which these screens are mounted are of the same length and since the relation between the screens and the links is such that the drive of the eccentric tends to throw the screens up owing to its eccentricity and allow them to drop down projecting the material forward there will be a constant travel of the material along each screen from the right hand toward the left hand end but since these screens are com- 115 paratively heavy the strain on the driving mechanism caused by changing their direction and their speed of movement will be considerable and I have provided, therefore, yielding means which tend to return each 120 screen to the neutral or central position. This yielding means takes the form of a spring or elastic member which tends to pull the two links of each pair into parallelism or into the position which they would occupy 125 130

when the screens are in their central or neutral positions, and of course, since the screens move in opposite directions, the tension on the spring will be greatly increased toward 5 the end of the stroke and thus the spring- stored energy in the spring will be sufficient largely to cause the return movement and thus to greatly assist the power mechanism in overcoming inertia of the screens.

10 The preferred form indicated in Figs. 4 and 5 provides an inclosed properly lubricated spring. The housing being a telescoping housing permits free movement of the parts and compression and expansion of the 15 spring at all times and the association of the two screens moving in opposite directions with their respective springs is such that the whole device may be a self-contained, self- balanced, screen structure.

20 I claim:—

1. A screening machine comprising two reciprocating screens one above the other, means for reciprocating them in unison in opposite directions and yielding means interposed between the two screens and lying wholly within said machine for resisting 25 their movement away from the central position said yielding means comprising coil springs attached adjacent the opposite ends 30 of the screens.

2. A screening machine comprising two reciprocating screens arranged one above the other, rocker arms upon which the screens are mounted, the arms for the upper screen 35 downwardly depending below their pivot points, for the lower screen upwardly extending above their pivot points and means applied to the ends of said rocker arms for reciprocating the screens in opposite directions, yielding means interposed between the 40 screen ends of the rocker arms on the two screens for resisting movement of the screens away from their central position.

3. A screening machine comprising two 45 reciprocating screens arranged one above the other, rocker arms upon which the screens are mounted, the arms for the upper screen downwardly depending below their pivot points, for the lower screen upwardly extending above their pivot and yielding means 50 applied to the screens comprising a spring arrangement adapted to resist separation of the screen ends of the supporting rocker arms of the two screens.

55 4. A screening machine comprising two reciprocating screens one above the other, means for reciprocating them in unison in opposite directions, shafts attached to each of said screens, sleeves mounted on said 60 shafts, a cylindrical lug projecting from one, a cylindrical housing from the other, a sliding connection between the lug and the housing, a plunger projecting outwardly from the lug and engaging the housing adjacent its supporting sleeve and a spring

interposed between the outer end of the housing and the plunger to resist separation of lug and housing.

5. A screening machine comprising two reciprocating screen plates, links upon which 70 they are supported, an eccentric driving shaft for the screens and eccentric rods extending therefrom to the screens, the links supporting the upper screen extending downwardly toward it thus supporting it, the 75 lower links extending upwardly toward the screen and supporting the lower screen, the eccentrics on the shaft which drive the eccentric rods being separated by an angle of 180°, yielding means tying together the 80 screen ends of the links of the two screens and adapted to resist movement of the screens away from their central position.

6. The combination with two reciprocating screens superimposed one above the other 85 of means for moving them in opposite directions in unison and yielding means interposed between the screens adapted to progressively and increasingly resist the movement of the two screens away from their 90 central positions.

7. A screening machine comprising two parallel reciprocating screens superimposed one above the other, means for moving them in opposite directions in unison, said means 95 lying substantially within the screening machine and yielding means interposed between the screens adapted progressively and increasingly to resist the movement of the two screens away from their central positions. 100

8. A screening machine comprising two reciprocating screen plates, a frame in which they are supported by links, an eccentric driving shaft for said screens located within said frame and eccentric rods extending 105 from the shaft to the screens, the links supporting the upper screen, extending downwardly toward it thus supporting it, the lower links extending upwardly and supporting the lower screen, the eccentrics on the shaft which drive the eccentric rods being separated by an angle of 180°, yielding means tying together the screen ends of the 110 links of the two screens, and adapted to resist movement of the screens away from 115 their central position.

9. A screening machine comprising a supporting frame, two horizontal screens, one above the other mounted in it by rocker arms and a yielding connection between the 120 said screens, means oscillating them in unison in opposite direction, situated within the frame and comprising an eccentric shaft and eccentric rods connected to the screens.

10. A screening machine comprising a supporting frame, two horizontal screens, one above the other, supported in it by rocker arms, means lying within the frame for oscillating them in unison in opposite direction and yielding tension exerting ac- 125 130

tion between them, adapted to resist said oscillatory motion.

11. A screening machine, comprising a frame, two screens within said frame, one superimposed above the other, the lower screen supported from below, and the upper screen supported from above, means located within said frame for oscillating said screens in unison in opposite directions, and yielding means lying substantially within said

frame, connecting said screens, and adapted progressively, and increasingly to resist said oscillatory motion.

In testimony whereof I affix my signature in the presence of two witnesses this first 15 day of February, 1919.

MATT OTTO.
